UNITED STATES PATENT OFFICE

2,077,483

REGULATOR

Henry C. Kestel, Toledo, Ohio, assignor to The
Myers Regulator Co., Toledo, Ohio

Original application January 4, 1934, Serial No.
705,183. Divided and this application January
20, 1936, Serial No. 59,882

1 Claim. (Cl. 74—424.5)

This application relates to gearing devices and more particularly to a gearing device which has been developed for use as the operating means for a pivotally mounted window and this application is a division of my prior application, Serial No. 705,183 filed January 4, 1934.

In that application there is disclosed a window having on its trunnions opposite edges, one of which is to be operatively connected to a stationary device which journals and supports the thus trunnioned edge of the window and is so formed as to enable a user to rotate the window on its trunnion axis by means of a handle of the device. This application relates specifically to such device.

For an understanding of the device, reference may be had to the accompanying drawing in which:

Fig. 1 shows the device partly in section and in front view.

Fig. 2 is a top plan view of the device.

Fig. 3 is a section as if on line 3—3 of Fig. 1.

A stationary part is indicated at 10. On this part is fixedly mounted a bracket 11 through which passes a shaft 12, the latter being formed with a squared recess 14 for receiving a squared trunnion of a window or the like whereby rotation of the shaft 12 will cause a trunnion received therewithin to be rotated on the axis of the shaft. The shaft 12 is restrained against axially shifting with respect to the bracket 11 by means of a pinion 15 fixed to the shaft and disposed above a plate 16 to which is secured a second plate 17, the two plates forming a housing 16—17 for the pinion 15, with the shaft 12 being journalled in the bracket and in the housing.

The edges of the plates 16—17 are spaced to permit the pinion 15 to pass therebetween as indicated in Fig. 3 and these edges are provided with flanges 18 which together form a base plate cooperating with a plate 19 to form a housing 18—19 for a scroll 21 meshing with the pinion 15. Journalled in a boss 22 of the plate 19 is a shaft 23 to one of whose ends is fixed the scroll and to the other one of whose ends is fixed a handle, not shown.

It is understood that the plates 16—17 and 18—19 are intersecured in pairs by means of lugs formed on the plates 17—19 projecting through slots of and clinched over the plates 16—18.

When the shaft 23 is rotated, the scroll will rotate therewith, and meshing with the pinion 15, will cause the latter and the shaft 12 fixed thereto to rotate about the axis of the shaft.

It will be observed that the two housings together form a single, T shaped housing within which are all of the operating parts of the device, and that the T cross bar housing 18—19 is adapted to form an escutcheon for a recess receiving the T leg housing 16—17.

For limiting travel of the pinion 15 there may be provided on and secured to the housing plate 16 a pin 26 received within a recess 27 of the pinion.

Now having described the device embodying the invention of this application, reference will be had to the claim which follows for definitions of the invention.

I claim:

An operating device comprising vertically and horizontally disposed meshing gear elements mounted to rotate on horizontal and vertical axes, respectively, horizontally and vertically disposed shafts fixed coaxially to said elements respectively and rotating therewith, the vertically disposed element being between the horizontal element and the horizontal shaft, horizontally and vertically disposed housings for the horizontally and vertically disposed elements respectively, the vertical housing comprising a large plate and two smaller coplanar spaced plates, with the vertical gear element being between the large plate and the two smaller plates, and with the horizontal gear element being between the adjacent edges of the two smaller plates, the horizontal housing comprising two small plates, each formed as an integral flange of one of the two smaller plates of the vertical housing, the flanges extending from the adjacent edges of the smaller plates of the vertical housing, the plates of the horizontal housing being spaced, with the horizontal gear element being in such space.

HENRY C. KESTEL.
